UNITED STATES PATENT OFFICE

JOSEPH N. PEPIN, OF CHICAGO, ILLINOIS

DESIGN FOR AN EMBLEM

Application filed April 6, 1933. Serial No. 47,708. Term of patent 3½ years.

To all whom it may concern:

Be it known that I, JOSEPH N. PEPIN, a citizen of the United States, residing at Chicago, in the county of Cook and State of Illinois, have invented a new, original, and ornamental Design for an Emblem, of which the following is a specification, reference being had to the accompanying drawing forming a part thereof in which the figure is a perspective view of an emblem showing my new design.

I claim:

The ornamental design for an emblem as shown.

JOSEPH N. PEPIN.
